DETACHABLE AND REPLACEABLE HEEL

Victor A. Lippert, Canton, Ohio, assignor of one-half to Richard D. Wernet, Canton, Ohio

Application May 13, 1937, Serial No. 142,447

4 Claims. (Cl. 36—36)

This invention relates to a heel construction for a shoe or the like, more particularly a heel construction having a detachable and replaceable traction or tread member formed of elastic material, such as rubber.

One object of the invention is to provide an improved heel having a tread member formed of yieldable, elastic material adapted to be removed and replaced or a new member substituted in a ready manner.

Another object of the invention is to provide an improved heel construction having a removable tread member formed of yieldable or cushioning material and which may be applied without the use of tools, nails, screws or other mechanical means, whereby the user may replace such member readily from time to time and maintain his heel at normal height.

A further object of the invention is to provide an improved heel construction comprising few parts which may be readily manufactured and applied to the sole of a shoe.

Other objects of the invention will be apparent to those skilled in the art to which my invention relates from the following description taken in connection with the accompanying drawing illustrating the preferred embodiment of the invention and wherein

Fig. 1 is a side elevation of a shoe having applied thereto a heel construction embodying my invention, parts being broken away.

Fig. 2 is a fragmentary bottom plan view of parts shown in Fig. 1.

Fig. 3 is a section on the line 3—3 of Fig. 2.

Fig. 4 is a section on the line 4—4 of Fig. 3.

Fig. 5 is a fragmentary view, partly in section and partly in elevation, with the tread member removed.

Fig. 6 is a view of the tread member, parts thereof being broken away.

Fig. 7 is a section on the line 7—7 of Fig. 3.

Fig. 8 is a plan view of the tread member.

Fig. 9 is a perspective view of the base member.

In the drawing, 1 indicates generally a shoe which may be of any desired construction and formed of suitable material. The shoe comprises an upper portion 2 and a sole 3. 4 indicates as an entirety the heel for the shoe and consisting of a base member 5 and a tread member 6. The heel 4 may be applied to the sole 3 when the shoe 1 is made and completed; where the shoe already is complete, its heel may be removed and a heel 4 substituted therefor.

The base member 5 is of a size and shape so as to conform to the side edges of the sole around the heel portion thereof and is formed of a suitable material that permits nails to be readily driven into and through it for which purpose wood may be employed. By preference, the member 5 is formed with a plurality of holes 5a to

receive in a ready manner nails 7, which are driven into the sole as shown in Figs. 1, 3, 5 and 7, the heads of the nails being preferably countersunk; but it will be obvious that screws may be used instead of nails. The inner face of the base member 5 is surfaced to conform to that of the sole so as to have bearing over its entire area; such surface in the illustrated construction being flat and fitting face to face with the sole when applied thereto. The inner side edge 5b of the base member 5 may be curvilinear, as shown in Figs. 4 and 9, consistent with the usual shape of heels. The side wall of the base member, adjacent its outer surface is cut-away to form an inwardly extending recess 8 and by preference this cut-away is arranged to accommodate the flange 9 provided on the tread member 6 so that when the latter is mounted or assembled on the base member 5, its outer side wall and the side wall of the base member are aligned with the side wall or edge of the sole to form a unitary substantially vertical side wall around the heel portion of the shoe 1. For this purpose, the bottom wall of the recess is substantially horizontal and its side wall is inclined downwardly and outwardly and terminates inwardly of the side wall of the member 5. The tread member 6 has a contour substantially similar to the base member 5 and is formed of rubber compounded to insure the desired cushioning effect and sufficient elasticity to permit of its ready attachment to and detachment from the base member 5, and when compounded it may have embedded in it a desired amount of abrasive material, such as emery dust to insure durability and non-slipping characteristics when in use. The tread member 6 consists of a tread portion 10 the inner surface of which rests against the outer surface of the base member 5 and an integral circumferential flange 9 (already referred to) the inner wall of which normally extends upwardly and inwardly, the cross sectional shape of the flange 9 being equal to the cross section of the recess 8. The flange 9 being formed of elastic material, it is capable of expansion laterally and hence may be stretched and distended over and around the side wall of the recess 8 and seated in the latter, as shown in Figs. 1, 3, 4 and 7, the normal tendency of the flange 9 to contract serving to maintain itself seated in the recess 8 whereby the tread member is secured in position. By expanding or stretching the flange 9, it may be readily removed. By preference, the recess 8 is formed around all sides of the base member 5 and the flange 9 likewise extends entirely around the tread portion 10, so that in the preferred form of construction the tread member is removably locked to the base member throughout its entire perimeter, and hence prevents displacement of the tread portion in any direction.

However, it will be obvious that the recess 8 may be omitted from the inner side wall of the base member 5. In this latter arrangement the engagement of the expandible flange 9 along the 5 corresponding wall of the tread member 6 with the inner side wall of the member 5 would serve, in cooperation with the rearward portions of the flange 9, to prevent any displacement of the tread member. Where the heel portion of the sole 10 curves inwardly for merging with the arch portion of the sole, as shown in the drawing, and since this curvature may be increased, if desired, the correspondingly inwardly curved portions of the flange 9 would serve to supplement the locking 15 effect of the flange 9 along the inner side wall of the tread member, as just described. Ribs 11 may be provided on the bottom surface of the tread member 5 by forming therein a plurality of shallow recesses or grooves 11a.

20 In the application of my heel construction to a complete shoe, the original heel thereon is removed and the base member 5 nailed, cemented or otherwise attached to the sole 3, as shown in Fig. 5, and thereafter the tread member 6 is positioned on the base member 5, as shown in Fig. 1.

It is desirable for many reasons to maintain all 25 portions of the heel at normal height for walking as well as for appearance sake. By my construction the ready detachment and attachment 30 of the tread member makes it possible to renew such member at will, at little expense, as once the base member is applied to the sole, any number of tread members can be replaced without the use 35 of tools, and fastening devices. It will be noted 40 that the inner wall of the flange 9 is inclined downwardly and outwardly so that the thickness of the flexible material at the point of union of the flange with the tread portion 10 is relatively narrow and therefore the flange may be readily flexed or stretched laterally outwardly to facilitate the application or removal of the tread member.

To those skilled in the art to which my invention relates many changes in construction and 45 widely differing embodiments and applications of the invention will suggest themselves without departing from the spirit and scope of the invention. My disclosures and the description herein are purely illustrative and not intended to be in 50 any sense limiting.

What I claim is:

1. A heel construction comprising a relatively 55 rigid upper lift adapted to be affixed to the bottom surface of a shoe, said upper lift having a peripheral downwardly outwardly diverging wall, and a rubber lift adapted for manual attachment and removal from said upper lift, comprising a bottom tread portion having substantially vertical outer walls and a peripheral upstanding flange 60 portion extending upwardly of said tread portion, said flange having normally upwardly and inwardly converging outer and inner walls, the inner walls converging inwardly at a more rapid rate than the outer walls and the peripheral dimensions of the inner walls being such as to require stretching of said walls to telescope said 65 walls over the peripheral outer walls of said upper lift, and the normal angle of convergence of said outer rubber lift walls being such that upon mutual attachment of said lifts said outer wall surfaces become substantially aligned with the substantially vertical outer walls of said tread portion, the portions of said flange walls adapted

to fit over said upper lift walls being substantially thinner than their height.

2. A heel construction comprising a relatively rigid upper lift adapted to be affixed to the bottom surface of a shoe, said upper lift having a 5 peripheral downwardly outwardly diverging wall, and a rubber lift adapted for manual attachment and removal from said upper lift, comprising a bottom tread portion having substantially vertical outer walls and a peripheral upstanding flange 10 portion extending upwardly of said tread portion, said flange having normally upwardly and inwardly converging outer and inner walls, the inner walls converging inwardly at a more rapid rate than the outer walls and the peripheral dimensions of the inner walls being such as to require stretching of said walls to telescope said walls over the peripheral outer walls of said upper lift, and the normal angle of convergence of said outer rubber lift walls being such that upon 20 mutual attachment of said lifts said outer wall surfaces become substantially aligned with the substantially vertical outer walls of said tread portion, the portions of said flange adjacent said tread portion adapted to fit over said upper lift 25 walls being substantially thinner than the height of said flange.

3. A heel construction comprising a relatively rigid upper lift adapted to be affixed to the bottom surface of a shoe, the lower peripheral portion of said upper lift having a downwardly outwardly diverging wall symmetrically related to the outer side walls of said lift, and a rubber lift adapted for attachment to and removal from said upper lift, comprising a bottom tread portion having substantially vertical outer walls and an integral, peripheral upstanding flange portion normally extending upwardly and inwardly of said tread portion, the outer and inner walls of said flange converging toward the tread portion and the said inner walls diverging outwardly at a more rapid rate than the adjacent outer walls and the peripheral dimensions of the inner walls being such as to require stretching of said walls to telescope the said walls over the peripheral 40 diverging walls of said upper lift, and the normal angle of convergence of the outer walls of said lower rubber lift being such that upon mutual attachment of said lifts said outer walls become substantially aligned with the substantially vertical outer walls of said tread portion and said outer side walls of said upper lift.

4. In a shoe, a heel base fastened to the shoe, and a rubber tread member, and interengaging portions for removably connecting said member 55 to said base and normally preventing removal movement of said member in all directions in its own plane, said interengaging portions comprising a continuous undercut wall on the lower side of said base and symmetrically related to the outer, lateral and inner side walls of the shoe heel and a continuous peripheral flange on said member normally extending upwardly therefrom and inwardly and having a cross section throughout its contour substantially complementary to the 60 recess formed by said undercut wall, the width of said flange at its outer end being less than the height thereof, said flange being arranged to be expanded laterally over said undercut wall whereby it yieldingly engages therewith to removably 65 secure said member to said base.

VICTOR A. LIPPERT.
